Fig. 2

Fig. 1

Fig. 3

Fig. 4

FIGURE 1 is a side elevational view of a Christmas stocking, showing my new design;

FIGURE 2 is a view in elevation showing the side opposite that seen in FIGURE 1;

FIGURE 3 is an end elevational view as seen from the lefthand portion of FIGURE 2; and

FIGURE 4 is an end elevational view as seen from the righthand portion of FIGURE 1.

My design for a cuffed Christmas stocking consists of an opaque rear face and an open or netted front face, which faces are connected at the sides and bottom by a binding or facing strip.

I claim:

The ornamental design for a Christmas stocking, substantially as shown and described.
